ISADORE GOLDSTEIN, OF NEW YORK, N. Y.

TONOMETER.

1,419,134.

Specification of Letters Patent. Patented June 13, 1922.

Application filed July 10, 1920. Serial No. 395,366.

To all whom it may concern:

Be it known that I, ISADORE GOLDSTEIN, a citizen of the United States, and a resident of the borough of Manhattan, in the city, 5 county, and State of New York, have invented a new and useful Tonometer, of which the following is a specification.

The invention is an improvement in tonometers, which are instruments for determining the tension of the eyeball, or the pressure of its fluid contents upon its walls, in glaucoma. The original method of palpating the eyeball by the finger tips was uncertain, and the instruments of the lever type which 15 have been employed are only approximately accurate. The object of this invention is to provide a delicate, accurate and easily read instrument for the purpose, utilizing a liquid, as mercury, which is displaced in a 20 capillary tube in accordance with the counterpressure of the eye when the instrument is allowed to rest, by its foot and a relatively movable plunger, upon the eyeball.

25 In the accompanying drawings, forming a part of the application, and illustrating the present preferred embodiment of the invention:

Figure 1 is an elevation of the instrument; 30 Fig. 2 is a vertical section on a larger scale, looking at right angles to Fig. 1, and with the tube broken away, full lines being used to show the normal projecting condition of the plunger before it has been applied to the 35 eyeball, and dotted lines showing the plunger relatively raised until it touches the diaphragm, which is the beginning of the indicating movement; and

Fig. 3 is a horizontal section on the line 40 3—3 of Fig. 2.

The instrument may be varied in respect to form and details of construction, and it will therefore be understood that I do not limit myself to the particular embodiment 45 which will now be briefly described.

The body of the instrument includes a member 1 having a broad, cup-like upper portion, and a downwardly projecting hollow stem 2, terminating in an expanded foot 3, the bottom 4 of which is concaved to conform substantially to the curvature of the eyeball. The upper portion of said member is formed externally with vertically spaced lateral flanges or shoulders 5, between which 50 is loosely confined an encircling holder 6, having suitable handle or grip portions 7 at

opposite sides. This holder, having a certain vertical freedom between the flanges, enables the operator to sustain the instrument laterally so as to rest in a vertical position on the eyeball, without the hand applying pressure thereto or removing it therefrom, so as to affect the reading. For convenience in assembling, the holder may be made in two halves, secured together by 65 screws 8.

The cup 1 is internally screw-threaded at the top to receive a second member, or nut, 9. This nut is concaved on the under side to afford a mercury reservoir 10, the bottom of 70 which is formed by a flexible wall or diaphragm 11. Said diaphragm may be secured to the nut by a flanged screw ring 12, with gaskets 13 at opposite sides of the margin of the diaphragm, between the same 75 and the ring and the nut, respectively, to prevent leakage.

The nut 9 is also formed with a central opening, the upper part 14 of which is of relatively large diameter and internally 80 screw-threaded, while the lower part has a small hole 15, opening into the top of the reservoir at its highest point. An upright tube 16 of glass or other transparent material, having a capillary bore, is secured, with 85 a leak-tight joint, at its lower end, in the chamber 14, by a gland nut 17 and packing rings 18 and 19, encircling the tube and between the end of the same, and the bottom of the chamber, respectively. 90

The upper end 20 of the tube is open, and enlarged to form a funnel entrance for fluid to charge the reservoir and column.

A plunger 21 passes through the stem 2 and foot 3, in which it is slidably guided. 95 Its upper end is provided with a suitable head 22 to act upon the diaphragm, said head being made of a separate piece screwed upon the body of the plunger so that the plunger length can be adjusted. Normally, that is 100 to say with the instrument held vertically and not resting on the eye, the plunger is sustained with its lower end projecting a moderate distance so as to form a sight to guide the application to the eye-ball, and its 105 upper end separated a distance from the diaphragm. Simple means for this purpose comprise a transverse pin 23 in the stem, passing through a vertically extending slot 24 in the plunger, this slot being of such 110 length and so positioned that, when its upper end rests upon the top of the pin, the con-

dition indicated obtains, while after the plunger has been raised until it touches the diaphragm there is room for sufficient further movement for the maximum range 5 of indication. The working or indicating movement does not begin until the plunger contacts with the diaphragm.

A scale, or scales, are provided whereby the condition of the eyeball is read directly 10 in millimeters of mercury from the displacement of the top of the column in the glass. A suitably graduated scale 25 may be applied directly to the tube, or a separate adjustable scale 26 may be mounted on a 15 vertical screw-threaded rod 27 rising from the nut member 17, nuts 28 on the rod above and below the movable scale enabling the same to be held at any desired elevation. A thumb-screw 29 threaded through the bottom 20 of the member 1 in position to bear against the bottom of the diaphragm enables the column to be adjusted for normal or zero position. The diaphragm 11 may be resilient or non-resilient and may be normally flat or may sag; and the scales may 25 be uniformly or non-uniformly graduated.

The displacement of the head of the column, which serves as the indication, is produced by the movement of the plunger relatively 30 to the foot, after the head of the plunger has been brought against the diaphragm by contact with the eyeball. Thereafter, the degree to which the plunger, bearing its proportion of the weight of the instrument, sinks into, or is resisted by the 35 eyeball, while the expanded and concaved foot of the instrument rests thereon, is the measure of the tension of the eye, and is registered by a lesser or greater rise of the 40 column in the glass.

What I claim as new is:

1. A tonometer comprising a body having a foot adapted to rest on the eyeball, a reservoir having a diaphragm forming its bottom, a glass tube in communication with the reservoir, a scale, and a plunger movable through the foot to act upon said diaphragm.

2. In a tonometer, a body having a foot 50 to rest upon the eyeball, a reservoir having a flexible wall, a glass tube in communication with the reservoir, and a scale, combined with a plunger movable through the foot and normally sustained in projecting 55 condition operatively separated from the flexible wall.

3. In a tonometer, the combination of a body having a foot to rest upon the eyeball, a reservoir having a diaphragm forming its bottom, a glass tube in communication with the reservoir, a plunger movable through the foot, and means normally sustaining the plunger in downwardly projecting condition with a space between its upper end 60 and the diaphragm.

4. A tonometer comprising a body having a foot to rest on the eyeball, a reservoir having a diaphragm forming its bottom, a glass tube in communication with the reservoir, a scale, and a plunger movable through the foot to act upon said diaphragm, the plunger normally resting by gravity away from the diaphragm.

5. A tonometer comprising a body member having a wide upper portion and a 75 downwardly projecting stem terminating in a foot to rest on the eyeball, a second member fixed in the wide upper portion of said body member and having a central opening and being recessed beneath to form a reservoir, 80 a diaphragm secured to said second member and forming the bottom of the reservoir, a tube secured in communication with the central opening of the second member, and a plunger slidable through the stem and 85 foot to act on the diaphragm.

6. A tonometer comprising a body member having a wide upper portion and a downwardly projecting stem terminating in a foot to rest on the eyeball, a nut 90 screwed in the top of said member and having a central opening and being concaved at the bottom, a diaphragm secured to said concaved bottom and forming therewith a reservoir, a tube secured in communication with the opening of the nut, a plunger slidable through the stem and foot to act on the diaphragm, and a pin in the stem normally sustaining the plunger separated 95 from the diaphragm.

7. A tonometer, comprising a body member having a wide upper portion and a downwardly projecting stem terminating in a foot to rest on the eyeball, the upper portion of said body member having vertically spaced lateral flanges, a holder encircling the body member loose between said flanges, a reservoir in said body member having a diaphragm bottom, a tube supported in communication with said reservoir, and a plunger slidable through the stem and foot to act upon the diaphragm.

8. In a tonometer, a body having a foot to rest upon the eyeball, a reservoir having a flexible wall, a glass tube in communication with the reservoir, and a scale, combined with a plunger movable through the foot and normally sustained in projecting condition operatively separated from the reservoir, and means whereby the length of 110 the plunger can be varied.

9. A tonometer comprising a body having a foot to rest on the eyeball, a reservoir having a diaphragm forming its bottom, a glass tube in communication with the reservoir, a scale, a plunger movable through the foot to act upon said diaphragm, and adjusting means active upon the diaphragm.
